[57] **CLAIM**

The ornamental design for a shoe outsole, as shown and described.

DESCRIPTION

FIG. 1 is a bottom plan view of a shoe outsole showing our new design;
 FIG. 2 is an elevational view of one side of the shoe outsole;
 FIG. 3 is an elevational view of the other side of the shoe outsole;
 FIG. 4 is a cross section taken along line 4—4 of FIG. 1;
 FIG. 5 is a cross section taken along line 5—5 of FIG. 1;
 FIG. 6 is a cross section taken along line 6—6 of FIG. 1; and,
 FIG. 7 is a cross section taken along line 7—7 of FIG. 1.
 The broken line showing of the upper in FIGS. 2-3 forms no part of the claimed design.

FIG. 4

FIG. 5

FIG. 6

FIG. 7
